OIL-BURNING BOILER-FURNACE.

1,364,502.

Specification of Letters Patent.

Patented Jan. 4, 1921.

Application filed May 15, 1918. Serial No. 234,707.

To all whom it may concern:

Be it known that I, DAVID J. IRISH, a citizen of the United States, residing at Barberton, in Summit county, State of Ohio, 5 have invented a new and useful Improvement in Oil-Burning Boiler-Furnaces, of which the following is a full, clear, and exact description, reference being had to the accompanying drawings, forming part of 10 this specification, in which—

Figure 1 is a partial longitudinal vertical section of a Stirling boiler provided with my improved oil burning furnace; Fig. 2 is a section on the line II—II of Fig. 1 15 looking downwardly; Fig. 3 is an enlarged detail view on a larger scale showing the burner arrangement with a modified form of hood; Fig. 4 is a view similar to Fig. 3 showing another form of hood; Fig. 5 is a 20 vertical section on the line V—V of Fig. 1, and Fig. 6 is a view similar to Fig. 5 showing separated air ducts for the burners.

My invention relates to the type of oil burning furnaces for boilers where the 25 burner pipes extend underneath the floor of the combustion chamber from the front of the ash pit and are provided with upwardly extending burners from which flames are projected forwardly into the combustion 30 chamber.

The object of the invention is to simplify and improve the construction, to make the burners and burner pipes easily replaceable and removable, and to improve the efficiency 35 of the structure.

In the drawings, referring to the form of Figs. 1, 2 and 5, 2 represents the mud drum of a Stirling boiler having the usual three banks of water tubes 3, 4 and 5 leading 40 upwardly to the steam and water drums. The furnace may, of course, be used with any desirable type of boiler. The refractory tile floor 6 of the combustion chamber 7 is preferably inclined downwardly and 45 rearwardly from the front wall 8, and supported on suitable framework, such as the transverse I-beams 9. The transverse bridge wall 10 preferably has a straight plain front face at the rear of the combustion 50 chamber and added to the front face of this bridge wall are the separating baffles 11 and 12. These baffles are arranged as shown in Fig. 2, so as to provide separators between the three burners 13 while affording 55 long transverse slots 14 which commun-

cate at their bottom ends with the ash pit space. The front portions of these slots are inclosed by the side extensions 15 of the separating baffles, the edges of which, in front of the boiler, are preferably chamfered or beveled forwardly and outwardly, as shown in Fig. 2, to allow for the diverging flames from the burners. The general shape of the flames is shown in dotted lines in Fig. 2. Over the tops of these separating baffles extends the refractory roof or hood 16 which projects above the burners and aids in deflecting the flame outwardly through the combustion chamber. The burner pipes 17 extend underneath the floor, 60 rest on suitable transverse supports 18 and carry at their rear ends the right angle branch burner pipes 19. The burner pipes may be slid back under the floor with the branch pipes horizontally until they are at 70 the rear of the floor, when, by reason of the slotted chambers 14, the burner pipes may turn upwardly into operative position, 75 registering with the slots in the baffles. In front of each burner, the floor is preferably provided with slots or holes 20, and, as shown in Fig. 2, the group of slots in front of each burner is preferably arranged in fan-shape so as to supply air under 80 the diverging fan-shaped flame from each 85 burner. As shown in this form, the hood 16 extends continuously across the bridge wall and is recessed into it.

The vertical slots, behind which the burners are located, extend to the floor of 90 the furnace chamber, and thus communicate throughout their entire height with the chambers 14. By this arrangement, an air space is provided to supply air directly from the air duct to the stream of oil and 95 steam as it issues from the burner. The lighter oils are immediately burned and this, in turn, causes a sudden and greater expansion and atomization of the heavier oils as the latter are projected into the furnace 100 chamber. This increased atomization lowers the quantity of steam that would be necessary for this purpose if the stream from the burner were projected into the furnace chamber through a mere hole in the baffle 105 wall. Particularly when the arrangement just described is used, I find it desirable to space the first air opening in the fan-shaped arrangement in the furnace floor away from the bridge wall, so as to give the lighter oils 110

time to burn with the air supplied through the lower part of the vertical slots, before a large quantity of air is supplied to the fuel stream through the floor.

5 In Fig. 3, I show a form similar to the first form except that the hood 16^a is inclined forwardly and upwardly, resting partly on the bridge wall and partly on the separating baffles.

10 In Fig. 4 I show a form similar to the first form except that the hood 16^b is shorter and more or less rudimentary.

The ash pit may be one continuous chamber, as shown in Figs. 1, 2 and 5, or the 15 air may be supplied to each burner slot or pocket separately by means of the separating partitions 21 shown in Fig. 6. This form of Fig. 6 is the same as the first form except for this separation of the ash pit 20 into separate air ducts for the air flowing back to each burner.

In the form of Figs. 1, 2 and 5, 22 are dampers at the front of the ash pit by which the air inlet thereto may be controlled.

25 In the form of Fig. 6 there will be one of these dampers for each of the air ducts, while in the first form as many of these dampers may be provided as may be desired.

The advantages of my invention result from the use of the transverse slots which allow the branch burner pipes to be turned up into position and from the continuous 35 supporting of the hood top, burner plate on the bridge wall and extensions without any arches or complex brick structures.

The fan-shape of the air openings 20 aids 40 in properly supplying air for complete combustion, while the front dampers control the air supplies desired.

What I claim and desire to secure by Letters Patent of the United States is—

1. In an oil burning furnace, a bridge 45 wall having a plurality of separate transverse pockets with openings into the combustion chamber, and a plurality of fuel pipes extending under the floor of the combustion chamber and each having an angular pipe extension adapted to be moved up 50 into place within one of said pockets, and a burner on the end of each pipe extension, said openings being narrower than the pockets and located directly in front of the burners and extending downward to the floor 55 of the furnace.

2. In an oil burning furnace, a bridge wall having a plurality of separate transverse hooded pockets with openings into

the combustion chamber, a plurality of fuel 60 pipes extending under the floor of the combustion chamber and each having an angular pipe extension adapted to be moved up into place within one of said pockets, and a burner on the end of each pipe extension, 65 said openings being narrower than the pockets and located directly in front of the burners and extending downward to the floor of the furnace.

3. In a furnace of the class described, a 70 floor, a bridge wall at the rear of the floor and having a sidewise elongated pocket, a fuel pipe having an angular extension arranged to be moved up into place within the elongated pocket, a burner on the end 75 of the angular extension, and air supply ports through the floor in front of the pocket and arranged in diverging form with the port nearest the pocket spaced from the bridge wall, said pockets being provided 80 with an opening narrower than the pocket and located directly in front of the burner and extending downward to the floor of the furnace.

4. In a furnace of the class described, a 85 bridge wall having a substantially flat front face, an added baffle wall in front of the bridge wall forming transverse pockets and provided with a top cover or hood extending horizontally and resting on the bridge 90 wall and added baffle, and oil pipes extending under the floor and having angular extensions arranged to be turned into position within the pockets, substantially as described.

5. In an oil burning furnace, a combustion chamber having a hood projecting toward the chamber, an air duct beneath the chamber, the floor of the chamber having a slot adjacent the bridge wall to connect the 100 chamber and the duct, a fuel pipe extending through the air duct to the slot, an angular pipe extension on the fuel pipe extending up through the slot and a single burner on the pipe extension and located beneath the hood, the fuel pipe, extension and burner being constructed and arranged to permit the burner to be swung into position through the slot by rotating the fuel pipe.

In testimony whereof I have hereunto signed my name in the presence of two subscribing witnesses.

DAVID J. IRISH.
